UNITED STATES PATENT OFFICE

2,515,621

STRIPPING MECHANISM FOR CARTON FORMING MACHINES

Franklin M. Willbrandt, Battle Creek, Mich., assignor to Battle Creek Bread Wrapping Machine Company, Battle Creek, Mich.

Application January 26, 1948, Serial No. 4,384

11 Claims. (Cl. 93—51)

1

This invention relates to improvements in stripping mechanism for carton forming machines.

The principal objects of this invention are:

First, to provide mechanism for quickly and positively stripping finished cartons from the forming blocks of a carton forming machine without damaging the finished cartons.

Second, to provide carton stripping mechanism which will advance with the forming blocks of the carton forming machine so that the cartons are stripped therefrom without stopping the forming mechanism of the machine.

Third, to provide novel mechanism for bringing friction stripper rolls into operative engagement with the forming blocks of a carton forming machine as the forming blocks are advanced uniformly through the machine.

Fourth, to provide a novel form of forming block for carton forming machines which is particularly adapted to cooperate with friction rolls for stripping cartons from the block.

Other objects and advantages pertaining to the details and economies of the invention will be apparent from the following description and claims.

The drawings, of which there are two sheets, illustrate a preferred form of my stripping mechanism.

Fig. 1 is an elevational view of my stripping mechanism as applied to a carton forming machine, portions of the framework of the forming machine being shown in cross section.

Fig. 2 is a fragmentary vertical cross sectional view along the line 2—2 in Figs. 1 and 4.

Fig. 3 is an enlarged fragmentary cross sectional view along the line 3—3 in Fig. 1.

Fig. 4 is an enlarged cross sectional view along the line 4—4 in Fig. 2.

Fig. 5 is a fragmentary plan view of the driving shaft and actuating cams and cam followers for the stripping mechanism.

My stripping mechanism is illustrated as applied to a carton forming machine having flights of carton forming blocks 1 mounted on a conveyor 2 for movement through the carton forming process of the machine. The conveyor 2 is driven by a chain 3 which carries a series of pressure blocks 4 associated with each flight of forming blocks and which is driven by a sprocket wheel partially illustrated at 5 in Fig. 1. The process by which cartons are formed on the forming blocks 1 is immaterial to the present invention and is therefore not illustrated. It is sufficient to state that the forming blocks 1 are

2

designed to have lined or unlined cartons 6 formed thereon and delivered from left to right as illustrated in Fig. 1.

The framework of the carton forming machine 5 is provided with a cross bar 7 of H-shaped cross section which extends transversely of the machine below the path of travel of the forming blocks 1 and which forms a support for a pair of brackets 8A and 8B positioned on either side of the path of travel of the forming blocks. The brackets 8A and 8B are provided with upturned ends 9 forming bearings for drive shafts 10. Bearing blocks 11 are secured to the brackets over the cross member 7 which form bearings for the opposite ends of the drive shafts 10. The drive shafts 10 are each provided with beveled gears 12 (see Fig. 4) which are arranged to be driven by mating beveled gears 13 secured to a cross shaft 14.

20 The cross shaft 14 is supported in brackets 15 (see Fig. 1) secured to the outer sides of the bearing blocks 11 and is provided at its forward end with a sprocket 16 arranged to be driven by the chain 17 from a large sprocket 18. The large sprocket 18 is carried on a cross shaft 19 mounted on the frame of the forming machine and is driven through the small sprocket 20 by a chain 21 from the driving sprocket of the conveyor chain 3.

25 30 The driving shafts 10 pivotally support a pair of racks 22A and 22B each of which is formed with a tubular lower rail journaled on the drive shafts and a pair of upstanding arms 23 forming intermediate journals 24 for a pair of roll shafts 25 and upper journals 26 for supporting a pair of guide rods 27. The racks 22A and 22B thus support the roll shafts 25 and guide rods 27 parallel to the path of travel of the forming blocks 1 and are tiltable toward and away from the sides of the forming blocks.

35 Positioned between each of the racks 22A and 22B and the bearing blocks 11 are a pair of driving gears 28 which are pinned to the drive shafts 10 and arranged to drive mating roll gears 29 pinned to the ends of the roll shafts 25. Each of the roll shafts 25 is provided with a stripper roll 30 having a soft rubber exterior and a splined driving connection to the roll shafts as illustrated at 31 so that the rolls rotate with the roll shafts but are movable axially therealong. The rolls 30 are each provided with hubs 32 having annular grooves formed therein arranged to receive the fork portions 33 formed on the lower ends of the shift members 34. The shift members 34 are mounted on the guide rods 27 and are

arranged to be moved axially therewith by mechanism to be described presently.

The rack members 22A and 22B are provided with inwardly extending arms 35A and 35B which are positioned in overlapping relationship as is most clearly illustrated in Fig. 2 so that the end of arm 35B overlies the end of arm 35A. Each of the arms 35A and 35B are urged downwardly by coil springs 36 secured to angle bars 37 attached to the support brackets 8A and 8B. The forward rack 22A is further provided with an outwardly extending arm 38 pivotally connected to a yoke 39. The shank of the yoke 39 is pivotally connected to a second yoke 40 carried on the lower end of a push rod 41. It should be noted that the pivotal connections between the yokes 39 and 40 and between the yoke 39 and the arm 38 are disposed at right angles to each other forming a universal joint.

The push rod 41 is provided with a yoke 42 at its upper end (see Fig. 1) which is pivotally connected by a link 43 to one arm of a crank member 44 carried on a stub shaft 45 secured to the frame of the machine. The crank 44 is arranged to be rocked on the shaft 45 by actuation of a second push rod 46 which extends between the crank 44 and the crank arm 47. The crank 47 is pivotally mounted on a cross shaft 48 extending between the sides of the machine. The crank 47 is held in place by the collar 491 and is provided with an actuating arm 49 arranged to be actuated by a cam 50 secured to the cross shaft 49. Thus as the actuating arm 49 is raised by the lift of the cam 50, the push rod 46 will be drawn to the left as shown in Fig. 1 and operating through the crank 44 will depress the push rod 41 to lower the crank arm 38 on the lower rail of the rack 22A. This motion will swing the rack 22A outwardly away from the forming blocks 1 and acting simultaneously through the arms 35A and 35B will swing the rack 22B outwardly away from the opposite side of the forming blocks. The cam 50 has a relatively short lift surface 53 extending between the ends of a constant retracting surface. The stripper rolls 30 will thus be moved away from the forming blocks as the arm 49 engages the lift surface 53. Obviously the shaft 49 and cam 50 must be rotated at such a speed as to complete one revolution while each flight is moving past the stripper mechanism.

The cross shaft 48 is provided on each side of the path of the forming blocks 1 with depending crank arms 51 which are secured to the shaft and pivotally connected to push rods 52 extending generally longitudinally to the shift blocks 34 mounted on the guide rods 27. The cross shaft 49 is provided with a second cam 512 which moves a second actuating arm 511 secured to the rock shaft 48. The rock shaft 48 is gradually rotated by engagement of the second actuating arm 511 with the cam 512. The depending arms 51 will be moved toward the stripper mechanism and the push rods 52 and shift blocks 34 will be actuated to move the stripper rolls 30 along the roll shafts 25. The cam 512 is provided with a continuously rising lift surface extending substantially around the cam to a quick return surface so that as the shaft 49 and cam are driven in timed relationship with the conveyor chain 3, the stripper rolls 30 will be advanced along the roll shafts 25 at the same speed and in timed relationship with each succeeding flight of forming blocks 1. The outward tilting action of the push rods 46 and 41 on the racks 22A and 22B is timed to coincide with the return stroke of the push

rods 52 so that the stripper rolls 30 are moved outwardly away from the forming blocks as they are moved back to register with a succeeding forming block.

Attention is now directed to a detail of the forming blocks 1 which are illustrated as being provided with a transverse recess 54 for receiving a pair of backing rolls 55. The rolls 55 are positioned so that their outer surface is substantially tangent to the surface of the forming blocks 1 so as not to interfere with the process of forming the cartons on the forming blocks but so as to readily back up the pressure of the stripper rolls 30 on the outer sides of the cartons 6. Thus as the stripper rolls 30 are brought into engagement with each succeeding carton 6, they will press the sides of the cartons and against the backing rolls 55 to obtain a positive frictional engagement with the sides of the carton. Since the stripper rolls 30 are constantly rotated by the gears 28 and 29 and shafts 10 and 14 each carton will be rapidly and positively stripped downwardly from its forming block and after passing from between the stripper rolls 30 will fall upon a discharge conveyor 56 for delivery to another portion of the forming machine.

If desired the cross shaft 14 may be provided with a chain drive 57 to a stub shaft and gear 58 for driving a date roll 59 positioned underneath the path of travel of the forming blocks so that as each carton is advanced across the dating roll, a date or other indicia will be printed on the bottom of the carton before the carton is stripped from the forming block.

I have thus provided stripping mechanism which will engage the cartons with sufficient pressure to have positive frictional engagement therewith so that no cartons will be left on the forming blocks. The stripping mechanism is further advanced with the forming blocks so there is no tendency for the rolls to tear or damage the cartons. The forming mechanism and flights of blocks 1 may be operated at a uniform high speed without being stopped to strip off the finished cartons. I have not attempted to show any modified forms of my stripper mechanism as several such minor modifications as may be desired should be apparent from the foregoing description.

Having thus described by invention, what I claim as new and desire to secure by Letters Patent, is—

1. Carton stripping mechanism for a carton forming machine having flights of carton forming blocks comprising, a cross member on said machine extending under the path of travel of said flights, a pair of brackets secured to said cross member on either side of the path of travel of said flights, a pair of driving shafts journaled in said brackets and parallel to said flights, a cross shaft journaled between said brackets and having gears thereon for driving said driving shafts, a rack tiltably mounted on each of said driving shafts and having roll shafts rotatably mounted therein, overlapping arms on said racks whereby outward tilting of one rack will tilt the other rack outwardly, gears for driving said roll shafts from said driving shafts, shift members slidably mounted on said racks for motion parallel to said roll shafts, stripper rolls rotatable with said roll shafts and slideable axially therewith, fingers on said shift members engageable with said rolls for imparting axial motion thereto, said racks being spring urged inwardly toward said flights, a second cross shaft driven in timed

relation to said flights to make one revolution as each flight passes said racks, a cam on said cross shaft having a relatively short lift surface and a constant retracted surface, a rock shaft extending transversely of said machine and having an actuator crank pivoted thereon and arranged to be actuated by said cam, one arm of said crank being link connected to said one of said racks to tilt said racks outwardly away from said flights upon engagement of said actuator crank with said lift surface of said cam, a second cam on said second cross shaft and having a constantly rising lift surface, an actuator arm secured to said rock shaft and arranged to be actuated by said second cam, a pair of crank arms on said rock shaft and link connected to said shift members to advance said shift members and rolls upon engagement of said actuator arm with said lift surface of said second cam whereby said rolls are advanced concurrently with each of said flights, and a pair of backing rolls recessed in each of said forming blocks and tangent with the side surfaces thereof, said backing rolls being positioned opposite said stripper rolls.

2. Carton stripping mechanism for a carton forming machine having continuously advanced flights of carton forming blocks comprising, a cross member on said machine, a pair of driving shafts supported on said cross member and parallel to said flights, a cross shaft supported on said cross member and having gears thereon for driving said driving shafts, a rack tiltably mounted on each of said driving shafts and having roll shafts rotatably mounted therein, overlapping arms on said racks whereby outward tilting of one rack will tilt the other rack outwardly, gears for driving said roll shafts from said driving shafts, shift members slidably mounted on said racks for motion parallel to said roll shafts, stripper rolls rotatable with said roll shafts and slidably axially therealong, fingers on said shift members engageable with said rolls for imparting axial motion thereto, said racks being spring urged inwardly toward said flights, a second shaft driven in timed relation to said flights to make one revolution as each flight passes said racks, a cam on said second shaft having a lift surface and a retracted surface, a crank having an actuator arm thereon arranged to be actuated by said cam, one arm on said crank being link connected to one of said racks to tilt said rack outwardly away from said flights upon engagement of said actuator arm with said lift surface of said cam, a rock shaft having a pair of crank arms and a second actuator arm thereon, a second cam on said second shaft and arranged to actuate said second actuator arm, linkage connecting said pair of cranks to said shift members to move said shift members and rolls whereby said rolls are advanced with each of said flights, and a pair of backing rolls recessed in each of said forming blocks and tangent with the side surfaces thereof, said backing rolls being positioned opposite said stripper rolls.

3. Carton stripping mechanism for a carton forming machine having continuously advanced flights of carton forming blocks comprising, a pair of driving shafts supported on said machine and parallel to said flights, a cross shaft supported on said machine and having gears thereon for driving said driving shafts, a rack tiltably mounted on each of said driving shafts and having roll shafts rotatably mounted therein, overlapping arms on said racks whereby outward tilting of one rack will tilt the other rack outwardly,

gears for driving said roll shafts from said driving shafts, shift members slidably mounted on said racks for motion parallel to said roll shafts, stripper rolls rotatable with said roll shafts and slidably axially therealong, fingers on said shift members engageable with said rolls for imparting axial motion thereto, said racks being spring urged inwardly toward said flights, a second shaft driven in timed relation to said flights, a cam on said second shaft, a crank having an actuator arm thereon arranged to be actuated by said cam said crank being link connected to one of said racks to tilt said rack outwardly away from said flights upon engagement of said actuator arm with said cam, a rock shaft having a pair of cranks link connected to said shift members, a second cam on said second shaft, a second actuator arm on said rock shaft engageable with said second cam to advance said shift members and rolls whereby said rolls are advanced with each of said flights, and a pair of backing rolls recessed in each of said forming blocks and tangent with the side surfaces thereof, said backing rolls being positioned opposite said stripper rolls.

4. In combination with a carton forming machine having continuously advanced flights of carton forming blocks, stripper mechanism for removing finished cartons from said blocks comprising, constantly driven drive shafts positioned on each side of the path of travel of said flights, tiltable racks supported on said drive shafts and tiltable toward and away from said flights, constantly driven roll shafts carried by said racks and having stripper rolls rotatable therewith and slidably axially therealong, said roll shafts being driven from said drive shafts, guide rods carried on said racks and parallel to said roll shafts, shift members on said guide rods having forks engaged with said rolls, arms extending from said racks in cooperating overlapping relation, springs urging said arms downwardly to converge said racks and stripper rolls on opposite sides of said flights, crank and link mechanism for tilting one of said racks away from said flights, said arms being operative to simultaneously tilt the other of said racks away from said flights, other crank and link mechanism for moving said shift members and rolls axially of said roll shafts, a cam driven in timed relationship to said flights for actuating said first crank and link mechanism in timed relationship with said flights whereby said rolls are converged on each of said flights, and a second cam driven in timed relationship with said flights for actuating said other crank and link mechanism for advancing said shift members and rolls with each of said flights, said forming blocks having backing rolls mounted therein tangential to the side surfaces thereof and opposed to said stripper rolls.

5. In combination with a carton forming machine having continuously advanced flights of carton forming blocks, stripper mechanism for removing finished cartons from said blocks comprising, tiltable racks supported on each side of the path of travel of said flights, constantly driven roll shafts carried by said racks and having stripper rolls rotatable with said shafts and slidably axially therealong, arms extending from said racks in cooperating overlapping relation, springs urging said arms downwardly to converge said racks and stripper rolls, crank and link mechanism for tilting one of said racks away from said flights, said arms being operative to simultaneously tilt the other of said racks away from said flights, other crank and link mechanism for advancing said shift members and rolls with each of said flights, said forming blocks having backing rolls mounted therein tangential to the side surfaces thereof and opposed to said stripper rolls.

6. In combination with a carton forming machine having continuously advanced flights of carton forming blocks, stripper mechanism for removing finished cartons from said blocks comprising, tiltable racks supported on each side of the path of travel of said flights, constantly driven roll shafts carried by said racks and having stripper rolls rotatable with said shafts and slidably axially therealong, arms extending from said racks in cooperating overlapping relation, springs urging said arms downwardly to converge said racks and stripper rolls, crank and link mechanism for tilting one of said racks away from said flights, said arms being operative to simultaneously tilt the other of said racks away from said flights, other crank and link mechanism for advancing said shift members and rolls with each of said flights, said forming blocks having backing rolls mounted therein tangential to the side surfaces thereof and opposed to said stripper rolls.

mechanism for moving said stripper rolls axially along said roll shafts, a cam driven in timed relationship to said flights for actuating said first crank and link mechanism whereby said rolls are converged against each of said flights, and a second cam driven in timed relationship with said flights for actuating said other crank and link mechanism for advancing said rolls with each of said flights, said forming blocks having backing rolls mounted therein tangential to the side surfaces thereof and opposed to said stripper rolls.

6. In combination with a carton forming machine having continuously advanced flights of carton forming blocks, stripper mechanism for removing finished cartons from said blocks comprising tilttable racks supported on each side of the path of travel of said flights and tilttable toward and away from said flights, constantly driven roll shafts carried by said racks and having stripper rolls rotatable with said shafts and slidable axially therealong, springs arranged to converge said racks and stripper rolls, a first crank and link mechanism for tilting said racks away from said flights, other crank and link mechanism for moving said stripper rolls axially along said roll shafts, a cam driven in timed relationship to said flights for actuating said first crank and link mechanism whereby said rolls are converged against each of said flights, and a second cam driven in timed relationship with said flights for actuating said other crank and link mechanism to advance said rolls with each of said flights, said forming blocks having backing rolls mounted therein tangential to the surfaces thereof and opposed to said stripper rolls.

7. In combination with a carton forming machine having flights of carton forming blocks, stripper mechanism for removing finished cartons from said blocks comprising tilttable racks supported on each side of the path of travel of said flights and tilttable toward and away from said flights, driven roll shafts carried by said racks and having stripper rolls rotatable with said shafts and slidable along the axes thereof, a spring arranged to converge said racks and stripper rolls, crank and link mechanism for tilting said racks away from said flights, other crank and link mechanism for moving said stripper rolls along the axis of said roll shafts, a first cam driven in timed relationship to said flights for actuating said first crank and link mechanisms whereby said rolls are converged against each of said flights, and a second cam driven in timed relationship to said flights for actuating said other crank and link mechanism for advancing said rolls with each of said flights, said forming blocks having backing rolls mounted therein tangential to the surfaces thereof and opposed to said stripper rolls.

8. Carton stripping mechanism for a carton forming machine having continuously advanced flights of carton forming blocks comprising, racks tiltably mounted on each side of the path of travel of said flights, continuously driven roll shafts mounted in said racks and parallel to the path of travel of said flights, stripper rolls having a soft rubber surface rotatable with said roll shafts and slidable axially therealong, cam actuated mechanism driven in timed relationship

with said flights and arranged to advance said rolls with each of said flights, other cam actuated mechanism driven in timed relationship with said flights and arranged to tilt said racks away from said flights after each advance of said rolls, and backing rolls recessed within each of said forming blocks and arranged to engage the inside of cartons formed thereon on the opposite sides of said cartons from said stripper rolls.

5 9. Carton stripping mechanism for a carton forming machine having continuously advanced flights of carton forming blocks comprising, racks tiltably mounted on each side of the path of travel of said flights, driven roll shafts mounted in said racks and along side of the path of travel of said flights, stripper rolls having a soft friction surface rotatable with said roll shafts and slidable along the axes thereof, cam actuated mechanism driven in timed relationship with said flights and arranged to advance said rolls with each of said flights, other cam actuated mechanism driven in timed relationship with said flights and arranged to tilt said racks away from said flights after each advance of said rolls, 15 and backing rolls recessed within each of said forming blocks and arranged to engage the inside of cartons carried thereon on the opposite sides of said cartons from said stripper rolls.

20 10. Carton stripping mechanism for a carton forming machine having flights of carton forming blocks comprising continuously driven stripper rolls having a soft rubber surface, means rotatably supporting said rolls on the opposite sides of the path of travel of said flights, said 25 means and stripper rolls being swingable toward and away from the sides of cartons formed on said blocks, said rolls being slidable on said means along their axis of rotation parallel to the path of travel of said flights, and means 30 driven in timed relation to said flights for actuating said stripper rolls including shift members for moving said rolls axially with said flights and push rods for swinging said rolls away from said flights at the end of each advancing motion 35 of said rolls.

40 11. Carton stripping mechanism for a carton forming machine having flights of carton forming blocks comprising continuously driven stripper rolls, means rotatably supporting said rolls on the opposite sides of the path of travel of said flights, said means and stripper rolls being swingable toward and away from the sides of cartons formed on said blocks, said rolls being slidable on said means along their axis of rotation, and 45 means for actuating said stripper rolls including shift members for moving said rolls axially with said flights and members for swinging said rolls away from said flights at the end of the advancing motion of said rolls.
